UNITED STATES PATENT OFFICE.

ROBERT C. RAHM, OF WYOMISSING, PENNSYLVANIA, ASSIGNOR TO TEXTILE MACHINE WORKS, INCORPORATED, OF WYOMISSING, PENNSYLVANIA.

BRAIDING-MACHINE.

No. 856,985.

Specification of Letters Patent.

Patented June 11, 1907.

Application filed October 14, 1904. Serial No. 228,393.

To all whom it may concern:

Be it known that I, ROBERT C. RAHM, a citizen of the United States, residing at Wyomissing, county of Berks, State of Pennsylvania, have invented certain new and useful Improvements in Braiding-Machines, of which the following is a specification.

My invention relates to an improved braiding machine adapted to produce a braided fabric which is made up of two simultaneously-formed braids laid one upon the other and having their threads interchanged in the process of manufacture so as to unite the two; a main object being to provide for producing various figured or embroidery effects by employing different colored carrier threads, by introducing different colored warp threads, and by providing for making a plurality of turns of certain of the carriers at determined points in their course, in connection with a regulated interchange of the carriers of the respective courses.

The invention is fully described in connection with the accompanying drawings and the novel features are specifically pointed out in the claims; the improved fabric which is referred to as produced thereby and process of making same being separately described and claimed in a divisional application, Serial No. 285,821, filed November 4th, 1905.

Figure 1 is a diagrammatic plan view of a braiding machine embodying my invention; a portion thereof showing the communicating race-circle courses with switches controlling the carrier movements therein, and the remaining portion indicating the pitch-circles of the carrier operating gears and the jacquard connections to the switches. Fig. 2 is an enlarged sectional view showing two gears of the outer course in mesh with two of the inner course, the section being on the line 2—2 of Fig. 1 straightened out. Fig. 3 is a diagram indicating the positions assumed by the carriers in operation.

The top plate *g* of a braiding machine is ordinarily provided with a single race-way or course for the bobbin carriers, formed by intersecting race-circles which are arranged concentric with a series of operating gears for the carriers. In Fig. 1 a portion of such a race-circle course is indicated at *h*, the race-circles of said course being concentric with a

series of intermeshing operating gears *b* indicated by their pitch circles. These horn 55 gears, as they are termed, are located between the top plate *g* and the bottom plate *k*, as shown in Fig. 2, and are provided with peripherally notched disks *b*¹ which engage the carriers to traverse the latter in their 60 serpentine course.

In my improved machine I provide a second complete race-circle course *m*, having a separate terminal gear arranged parallel with the course *h*, and having the same number of 65 race-circles, each arranged tangential to an adjoining circle of the inner course so as to afford communication between the two whereby the carriers of each course may be diverted into the other. To regulate this 70 interchange of carriers, a series of switches *c c c* is provided between the two courses, the points of which switches are adapted to open or close such communication as determined by the position to which they are swung upon 75 their pivotal supports: This position being automatically controlled, as indicated, by a suitable jacquard mechanism *j* and wires *i* extending therefrom to the switches.

As shown in Fig. 1, the parallel race-circle 80 courses *h* and *m* are arranged concentric, with the race-circle centers of both courses on the same radial lines, but with increased race-circle diameters in the outer course as required. The horn-gears of both courses 85 being arranged for the same number of carriers, it is necessary that they be rotated in equal times notwithstanding the necessary difference in diameters. This is conveniently accomplished, as indicated in Figs. 1 and 2, by 90 arranging the gears of the inner course in mesh with each other, and each of the outer gears in mesh only with an adjacent inner gear; the outer gears, though of somewhat larger diameter, being provided with only 95 the same number of teeth as the inner gears so as to be rotated in the same time. These so-called "bastard gears" are readily cut so as to mesh properly with the closer-pitched teeth of the inner gears.

When each set of carriers is held to its own course two separate braids will be formed, the runs being as indicated in Fig. 3. The manner of accomplishing this will be understood by reference to Fig. 1, in which it will 105 be seen that the carrier indicated at *e* will be

held to its normal outer course by the switch *c* when the latter is set as shown; and that the turning of said switch immediately after the passage of said carrier *e* will serve in like manner to retain the carrier *d* upon its normal inner course. Thus in order to retain the carriers in their respective outer and inner courses the switches *c* must be kept swinging from one side of the run to the other, in proper time, by the jacquard mechanism. The separate braids thus produced will be of different colors if the carriers of the two runs are provided with differently colored yarns. If the switch *c* however be moved to reverse positions to those just considered then the carrier *e* would be caused to pass into the inner course and the carrier *d* into the outer one; and being of different colors *d* would, for instance show as white in black on the outer, and *e* as black in white on the inner side of the product, while at the same time uniting the otherwise independent braids in a single fabric.

To enable the securing of additional ornamental effects in connection with the interchanging of the outer and inner course threads, provision is made for causing any desired carrier to make a plurality of turns on a given gear or gears before pursuing its normal course. For this purpose a second series of switches *o*, as shown, are so arranged as to permit a temporary reversal of any carrier movement. In this connection also, the outer course is shown provided with loops *n* adapted to set back carriers whose motion has been thus reversed, in order to avoid collisions which would otherwise result. The carriers are traversed in these loops by gears indicated at *p* Fig. 1, which, as shown, are each driven by an adjacent outer-course gear *a* and are provided with only two carrier-engaging horns instead of the four provided on gears *a* and *b*. Another series of switches *r* are provided to put these carriers into or out of action as determined by the jacquard. Provision is also made for introducing warp threads of desired colors into the fabric, either through the spindles of the gears or the switch posts or both as indicated at *s* and *t* in Fig. 1, around which warps the carrier threads are laid so as to cover or to show them as required for different figure effects.

It will be readily understood that the mechanism described enables a very great variety of ornamental effects to be produced in a fabric made up of two braids the threads of which are interchanged as stated and also that the preferred construction and arrangement of parts specifically shown and described may be modified without departing from the invention.

What I claim is:—

1. A braiding machine comprising two parallel communicating race-circle courses

having separate terminal gears, carriers traversing said courses, switches controlling the movement of said carriers from one course to the other, and separate switches arranged at right angles to the main switches.

2. A braiding machine comprising two parallel communicating race-circle courses having separate terminal gears, carriers traversing said courses, and switches controlling the movement of said carriers from one course to the other.

3. A braiding machine comprising two parallel communicating race-circle courses having separate terminal gears, carriers traversing said courses, switches controlling the movement of said carriers from one course to the other, and separate means for temporarily reversing the movement of certain of the carriers as desired.

4. A braiding machine comprising two parallel communicating race-circle courses having separate terminal gears, one of said courses having set-back loops, carriers traversing said courses, switches controlling the movement of said carriers from one course to the other, and separate reversing and loop switches.

5. A braiding machine comprising two parallel communicating race-circle courses having separate terminal gears, carriers traversing said courses, hollow warp-thread spindles around which the carriers swing, and switches controlling the movement of the carriers from one course to the other.

6. A braiding machine comprising two parallel communicating race-circle courses having separate terminal gears, carriers traversing said courses, hollow warp-thread spindles between the two courses, and switches controlling the movement of said carriers from one course to the other.

7. A braiding machine comprising two parallel communicating race-circle courses having separate terminal gears, carriers traversing said courses, switches controlling the movement of said carriers from one course to the other, and hollow warp-thread spindles for said switches.

8. A braiding machine comprising two concentric communicating race-circle courses having separate terminal gears, carriers traversing said courses, and switches controlling the movement of said carriers from one course to the other.

9. A braiding machine comprising two concentric courses having radially aligned inter-communicating race-circles with separate terminal gears, carriers traversing said concentric courses in equal times, and switches controlling the movement of said carriers from one course to the other.

10. A braiding machine comprising two concentric courses having radially aligned inter-communicating race-circles with separate terminal gears, an inner circle of intermesh-

ing horn-gears, a corresponding outer circle of similar horn gears of larger diameter driven in unison with said inner circle of gears, carriers traversed uniformly in the respective courses by said gears, and switches controlling the movement of said carriers from one course to the other.

In testimony whereof, I affix my signature, in the presence of two witnesses:

ROBERT C. RAHM.
